O. H. Melandy

UNITED STATES PATENT OFFICE.

O. H. MELENDY, OF DELHI, IOWA.

IMPROVEMENT IN SEEDING-MACHINES.

Specification forming part of Letters Patent No. **23,481**, dated April 5, 1859.

To all whom it may concern:

Be it known that I, O. H. MELENDY, of Delhi, in the county of Delaware and State of Iowa, have invented a new and useful Improvement in Seeding-Machines; and I do hereby declare that the following is a full, clear, and exact description of the same, reference being had to the annexed drawings, making a part of this specification, in which—

Figure 1 is a side sectional view of my invention, taken in the line *x x*, Fig. 2. Fig. 2 is a plan or top view of the same.

Similar letters of reference indicate corresponding parts in the two figures.

To enable those skilled in the art to fully understand and construct my invention, I will proceed to describe it.

A represents a horizontal frame, which is mounted on two wheels, B B'; and C is a driver's seat, which is placed on the frame A, directly over the axle D' of the wheels B B'. On each side of the frame A, and directly in front of each wheel B, a seed-box, D, is placed, and E is a slide, which is placed transversely in the under side of the front part of the frame A and allowed to work freely therein. This slide E has holes *a* made through it—one near each end—and the ends of the slide work underneath or at the lower parts of the seed-boxes D D, the slide resting or working on plates *b*, which are attached to the lower ends of the seed-boxes. (See Fig. 1.)

To the under side of the frame A, near its front part, a lever, F, is attached by a fulcrum-pin, *c*, and the front end of this lever is attached by a pivot, *d*, to the slide E at about its center. The back end of the lever F is attached by a pivot, *e*, to a slide, G, which works in proper guides attached to the under side of the frame A, and to the slide G the lower end of a vertical lever, H, is attached, said lever extending upward in front of the seat C. To a certain number of spokes, *f*, of the wheel B' oblique or beveled projections *g* are attached, said projections extending inward, as shown clearly in Fig. 2. These projections may be formed of metal strips bent in loop form, and they may be attached to the spokes by screws. The outer end of the slide G projects beyond the side of the frame A and within the plane of the movement of the projections *g*. Against the back end of the lever F a spring, *h*, bears.

To the front part of the frame A, and at each

side, a curved bar, I, is attached by a pivot, *i*. These bars are allowed to swing loosely on their pivots, and in the lower end of each bar a rotary cutter, J, is fitted. The bars I are connected by links *j* to similar bars, K, the upper ends of which are also pivoted in the under side of the frame A, as shown at *k*; the bars being allowed to swing freely on their pivots. The links *l* are simply metal bars pivoted at their ends to the bars I K, as shown clearly in Fig. 1. To the upper surface of each bar K a rod, *m*, is attached, and these rods pass through the frame A, and are attached to a traverse-bar, L, on the frame A. To the center of the bar L a lever, M, is attached, said lever having its fulcrum at *m'* and extending back near the seat C.

To the lower ends of the bars K standards *n* are attached—one to each—and to each standard a share, *o*, is secured. These shares are of the shovel or cultivator form, and are placed directly behind the rotary cutters J, as shown clearly in Fig. 1. To each bar K two bars, N N, are attached—one at each side—said bars having each a covering-share, *p*, attached to its back end.

To the back part of the frame A, and at equal distances from its center, bars O P are placed, said bars corresponding to the bars I K, and having attached to them, respectively, rotary cutters Q and shares R, corresponding with the cutters J and shares *o* of the bars I K, the bars O P being connected by links *j'*, and the bars P connected by rods *m''* to a lever, *m*, which corresponds to the lever M of the bars K. The cutters Q and shares R may be used as cultivators only. In the latter case covering-shares *p* may be dispensed with.

The operation is as follows: As the implement is drawn along the cutters J divide all roots, weeds, &c., that may lie in their path. The shares *o* make the necessary furrows to receive the seed, which is discharged from the boxes D D in consequence of the reciprocating movement given the slide E by the action of the projections *g* of the spokes *f* on said slide, in connection with the spring *h*, the holes *a* filling with seed when they are within the seed-boxes, the seed being discharged therefrom as the holes are withdrawn from underneath the seed-boxes. In case obstructions lie in the paths of the shares *o* the latter are elevated above them by the bars I and cutters

J. The latter of course, in consequence of their rotation, readily pass over abrupt prominences of moderate dimensions, but the shares *o* cannot unless elevated. In consequence, therefore, of having the bars I K connected by the links *j*, the upward movement of the bars I will be transmitted to the bars K, and the shares *o* therefore will be made to readily pass over obstructions. This is an important feature of the invention, as the shares *o* would be otherwise caught and retained by obstructions, causing great delay and embarrassment, especially in ground that is not under a most perfect state of cultivation.

It will be seen that the operator has perfect control of the seed-distributing device through the medium of the lever H. This lever can be actuated by the knee of the operator, and the dropping of the seed retarded or expedited at particular times, as may be necessary for

the planting of the seed in check-rows. It will also be seen that both the rotary cutters J Q and the shares *o* R may be elevated by actuating the levers M M'.

I do not claim, broadly, the employment or use of a reciprocating seed-slide, E, for they are well known and in common use; but,

Having thus described my invention, what I claim as new, and desire to secure by Letters Patent, is—

The levers F H, slides E G, and projections *g* on the wheel B', in connection with the bars I K O P, connected by the links *j* *j*', the whole being arranged substantially as and for the purpose set forth.

O. H. MELENDY.
